UNITED STATES PATENT OFFICE.

ROLLIN C. LEWIS, OF STAMFORD, CONNECTICUT, ASSIGNOR TO THE YALE & TOWNE MANUFACTURING COMPANY, OF STAMFORD, CONNECTICUT.

COMBINATION-LOCK.

1,092,843.

Specification of Letters Patent. Patented Apr. 14, 1914.

Application filed July 25, 1913. Serial No. 781,141.

To all whom it may concern:

Be it known that I, ROLLIN C. LEWIS, of Stamford, in the county of Fairfield and State of Connecticut, have invented certain 5 new and useful Improvements in Combination-Locks; and I do hereby declare the following to be a full, clear, and exact description of the invention, such as will enable others skilled in the art to which it appertains to make and use the same.

My invention relates to an improvement in combination locks, one object of which is to provide improved means for locking the cover plate to the lock casing.

15 A further object is to provide improved means for locking the part of the casing carrying the tumblers to the part of the casing carrying the means for actuating the tumblers.

20 With these and other objects in view my invention consists in the parts and combination of parts and in details of construction as will be more fully explained and pointed out in the claims.

25 In the accompanying drawing Figure 1 is a view in elevation showing the lock case carrying the cam, bolt and fence, and the cover plate removed and showing the tumblers and cover plate locking means carried

30 by the same. Fig. 2 is a view in longitudinal section with the cover plate and tumblers in place. Fig. 3 is a view of the cover plate, the tumblers being removed and showing the locking plate and key lock for actuating the same. Fig. 4 is a view of the locking plate detached and Fig. 5 is a view showing the manner of locking the two sections of the tumblers together.

35 1 represents the lock case carrying the 40 meshing gear wheels 2 and 3, the former of which is fixed to the dial spindle 4, and the latter to the hollow shaft 5 on which the hub 6 of the fence 7 is mounted, the hub being frictionally mounted on the hollow shaft 5

45 so as to tend to rotate with said shaft, and will rotate with same until stopped by contact with the parts which coat with the fence. The hollow shaft 5 is mounted on the screw stud 5^a screwed into the front face of

50 the lock casing. As the two gears 2 and 3 are always in mesh, it follows that when the spindle 4 is rotated, the shaft 5 will be rotated in the opposite direction. The spindle 4 which carries the dial 4^c, passes through

55 the front plate of the lock case, and carries

the gear wheel 2, and the cam 9, the gear wheel being located adjacent the inner surface of the front plate of the lock case, and the cam immediately behind the gear wheel. The fence 7 which is also carried by the lock case, is operated by the cam to retract and project the bolt in the usual and well known manner. Each tumbler is disk shaped and is composed of an inner disk 8^a and an outer disk 8^b. These disks are loosely mounted on the sleeve 4^a fixed to or integral with the front or inner face of the cover plate 17, and are rotated by the cam 9, and by the next adjacent tumbler in sequence starting from the cam, the cam and tumblers having the usual engaging means. The inner disk 8^a of each tumbler is serrated on its periphery and each outer disk 8^b is provided with a central opening of a size sufficient to receive the inner disk so that when the two disks or tumbler sections are assembled and locked together, they form in effect a single disk structure with a central opening to receive the sleeve 4^a on which the several tumblers are mounted to rotate. The outer section 8^b of each disk is hollowed out and carries a locking lever 10 fulcrumed at 11, and acted upon at one end by a spring 14, which normally tends to hold the serrated end 12 of the lever out of contact with the serrated periphery of the inner section of the tumbler. The serrated end of each lever projects through the inner wall of the outer disk of the tumbler, and is of a length sufficient to engage a plurality of serrations or teeth on the periphery of the inner section 8^a, and solidly lock the two parts against independent rotation. Located adjacent the other end of said lever of each disk is the cam 15 adapted to force the serrated end of its lever into contact with the serrated surface of the inner section of the disk and lock the two sections against independent movement. By turning the cam in one direction the lever will be released thus permitting the spring 14 to force the serrated end of the lever away from the serrated edge of the inner disk, and by turning the cam in the opposite direction, the lever will be forced into contact with the serrated edge of the inner section 10 of the disk thus locking the two sections of the disk together. Each cam has a key opening 15^a through the same, and the openings in the several cams are so located with relation to the periphery of the latter, that when 110

the tumblers are properly set up, the key openings are in alinement with each other and with an opening in the cover plate, so that by introducing the proper key and 5 turning same, the entire series of levers carried by the outer sections of the tumblers will be actuated to release the tumbler sections whereby the inner sections may be turned to change the combination, which 10 may then be done in the usual and well known manner. With this construction the cam is mounted in the lock case adjacent the front wall thereof, and is secured to the spindle shaft 4 and the tumblers 15 are all nested on a support carried by the cover plate and are adapted, when the cover plate is placed on the case, to engage the cam so as to be actuated by the same in the usual and well known manner. 20 The fence 7, is as before explained, mounted on the hollow shaft 5, which is connected with gear wheel 3. The hub 6 of this fence is a friction hub, in that it is provided with means which make contact with the 25 hub with sufficient friction to cause the fence to move, and tend to move in the direction of rotation of said shaft, so that the rotation of the gear 3, during the movement to set up the tumblers for unlocking, carries 30 the fence away from the peripheries of the tumblers, and holds it so removed until the direction of rotation of the gear is reversed for retracting the bolt. The fence 7 is provided with an arm 7^a adapted to rest within 35 a slot 16^a in the bolt 16, and with a second arm 7^b adapted to enter the notches 8^c in the peripheries of the tumblers, and also the notch 9^a in the cam 9. When the spindle shaft 4 is turned to the 40 right, as in setting up the tumblers for unlocking, the fence will be turned so that its arm 7^b will be carried out of contact with the peripheries of the tumblers and the cam, the slot 16^a in the bolt, being of a size and 45 shape to permit such movement. Upon reversing the direction of movement of the spindle shaft 4, the fence will be turned so as to bring its arm 7^b over into contact with the peripheries of the cam and tumblers, 50 and as the notch 9^a in the cam comes into alinement with the notches in the tumblers, the friction between the shaft and hub of the fence carries the arm 7^b of the fence into said notches, and the continued movement of 55 the cam 9 acting on the arm 7^b of the fence turns the latter in a direction to retract the bolt 16. The bolt 16 is slidingly mounted against the inner surface of the front plate of the lock case, and is slotted to receive the 60 spindle 4 and the fence 7.

The tumblers 8 are mounted on the sleeve 4^a, which in the present instance is cast integral with the front or inner face of the cover plate 17, and are held thereon by the 65 split collar 4^b detachably secured to the end

of sleeve 4^a in advance of the first tumbler therein. These tumblers are further sustained and supported by the ring plate 27 which latter is secured by screws to the studs 28^a integral with the cover plate. The ring plate 27, as its name implies, is open at its center to permit the engaging means on the cam to engage the next adjacent tumbler, as is necessary in the operation of the lock. 70

Mounted on the sleeve 4^a or preferably on an enlargement of the same, and resting against the front or inner surface of the cover plate 17 is the cover locking plate 28. This plate is preferably provided with the tongues 29 projecting from the periphery of the cover locking plate and moving within slots in the guides 30, which latter operate to hold said locking plate in place when the tumblers are removed, the guiding slots in the guides 30 being of a length sufficient to 80 permit of a part rotary motion of said locking plate. This locking plate is also provided, preferably at diametrically opposite points, with the forwardly projecting lips 31 having outwardly turned ends 32, which latter are adapted, when the locking plate is turned, to enter locking slots 33 in the lock case and absolutely lock the cover plate to the case, and is further provided with a forwardly projecting lug 34, which latter rests within an elongated slot in the cam 35 of the pin tumbler lock 36, so that when the cam 35 of the lock 36, which is secured to and carried by the cover plate of the lock, is turned, the cover locking plate 28 will be turned to 90 either carry the bent ends 32 of the lips 31 into or out of the slots 33, thus locking or releasing the cover plate as the case may be. This cover locking plate is also provided with a hole 37, which when the plate 28 is 100 turned to a position to release the cover plate, alines with the key hole in the latter so that in order to introduce the key used for actuating the levers which lock the disk sections of the tumblers together, it is first 105 necessary, with the construction as herein illustrated, to rotate the cover locking plate by its key into its unlocking position. But it is apparent that the key hole in the cover locking plate could be made to aline with 110 the key hole in the cover plate when the locking plate is in its locking position. 115

The cover locking plate 28 is of slightly greater diameter than the tumblers 8, and its periphery is cut away adjacent the fence so as not to interfere with the free passage of the arm 7^b of the latter into the slots in the tumblers, and this cut away portion is so shaped at one end as to form a finger 38, which, when the cover locking plate is 120 turned to its unlocking position, engages the rear end of arm 7^b of the fence and holds the latter away from and out of contact with the peripheries of the tumblers. The tumblers are all nested in the cover plate of the 125 130

lock, so that when the cover plate is applied to the lock case the tumblers bear proper operative relation to the cam and fence.

To change the combination, the door carrying the lock is opened, and the key inserted in the lock carried by the cover plate of the lock and turned in a direction to release the cover. This brings the key hole in the cover locking plate into alinement with the key hole in the cover plate, and after the key openings in the cams of the several tumblers have been brought into alinement with each other and with the key hole in the cover plate, and cover locking plate, the key can be inserted through the cover plate and turned to actuate the cams in a direction to disconnect the levers 10 from the inner sections of the tumbler sections, thus leaving said inner sections free to be turned by the dial spindle to set up the tumblers on any desired combination.

In order to change the combination, the cam and connected inner sections of the tumblers must be free to turn, while the outer sections of the tumblers are held against movement. This is made possible by having the cam at the front and the tumblers in rear of the cam, the cam forming a stop against which the end of the key may abut. While I have referred to the inner disks 8^a of the tumblers as having serrated peripheries, this is not essential, as the levers 10 may have bearing sufficiently extensive on the inner disks to hold them by friction alone, but I prefer to serrate the disks and have so shown them in the drawings.

It is evident that many slight changes might be resorted to in the relative arrangement of parts shown and described without departing from the spirit and scope of my invention. Hence I would have it understood that I do not wish to confine myself to the exact construction and arrangement of parts shown and described, but

Having fully described my invention what I claim as new and desire to secure by Letters-Patent, is:

1. In a combination lock, the combination of a lock casing, a cam, means carried by the casing for rotating the cam, a cover plate, a tumbler carried by the cover plate and removable with the same, means connecting the cam and tumbler whereby the latter is rotated by the former, and a device pivoted to the cover plate and adapted to engage the lock casing at a plurality of points for locking the cover plate to the casing.

2. In a lock, the combination of a lock cas-

ing, a bolt and bolt actuating means within the casing, a cover plate, a locking device 60 movably mounted on said cover plate and adapted to engage the casing for locking the cover plate to the casing, and a lock independent of the main lock for shifting the locking device to its locking and unlocking 65 positions and also for locking said locking device against movement.

3. In a combination lock, the combination of a lock casing, a bolt and bolt actuating means within the casing, a cover plate for 70 the casing, a cover locking plate mounted to turn on said cover plate, and a key lock and connections whereby said locking plate may be turned to release and lock the cover plate to the casing and be locked against 75 turning movement.

4. In a combination lock, the combination of a lock case, a cam journaled therein, a sliding bolt, a fence intermediate the cam and bolt for actuating the latter, a cover 80 plate for the lock, a series of tumblers nested on a bearing rigid with the cover plate, and a device also carried by the cover plate and actuated by a key lock on the latter for holding the fence out of contact with the cam 85 and tumblers while the combination of the lock is being changed.

5. In a combination lock, the combination of a lock case, a cam and tumblers therein, a sliding bolt, a fence intermediate the cam 90 and bolt for actuating the latter, a cover plate for the lock and a device carried by the cover plate and actuated by a key lock on the latter for locking the cover plate to the casing and for holding the fence out of contact with the cam 95 while the combination of the lock is being changed.

6. In a combination lock, the combination of a lock case, a cam therein, a sliding bolt, a fence intermediate the cam and bolt for 100 actuating the latter, a cover plate for the lock, a series of tumblers nested on a bearing rigid with the cover plate and a device also carried by the cover plate and actuated by a key lock on the latter for locking the cover 105 plate to the casing and also for holding the fence out of contact with the cam and tumblers while the combination of the lock is being changed.

In testimony whereof, I have signed this 110 specification in the presence of two subscribing witnesses.

R. C. LEWIS.
